UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

WAIST-LASTING MACHINE.

1,202,023.

Specification of Letters Patent. Patented Oct. 24, 1916.

Application filed August 28, 1912. Serial No. 717,501.

To all whom it may concern:

Be it known that I, MATTHIAS BROCK, a citizen of the United States, residing at Boston, in the county of Suffolk and State 5 of Massachusetts, have invented certain Improvements in Waist-Lasting Machines, of which the following description, in connection with the accompanying drawings, is a specification, like reference characters on 10 the drawings indicating like parts in the several figures.

This invention relates to machines for use in the manufacture of boots and shoes and particularly to machines adapted for 15 lasting the waist of a shoe or perfecting the lasting of that portion of the shoe. As is well understood a shoe upper is open at the top and the throat between the flies and cannot therefore be stretched to the same extent in lasting the shank that it can be in 20 lasting the forepart. The shank is therefore usually laid in and fastened to the innersole without much tensioning and sometimes it happens that objectionable fullness 25 appears in the waist or middle portion of the shoe.

It is the object of this invention to remove such fullness and, it may be, to tension the waist portion of a shoe so that a trimmer 30 and better fitting appearance will be produced in shoes.

This invention comprises an apparatus having means for seizing a shoe fly and holding it while the shoe with the last in it 35 is manipulated to pull the upper from the shank region toward the fly in combination with means for thereafter inserting a fastening to secure the fly to the last. Preferably the holding means is movable, with 40 the shoe having the upper under tension, to present the work to the inserting means. The seizing means is advantageously formed to engage the fly at an eyelet or buttonhole through which the fastening is inserted to 45 secure the fly without damaging it and also the apparatus may be provided with means suitably arranged to enable the operator to 50 fulcrum the shoe against it for pulling the upper for the purpose stated. These and other features of the invention, including certain details of structure and arrangement, will be more fully disclosed in connection with the following description of a

preferred machine and will then be more particularly pointed out in the claims. 55

Figure 1 is a left hand side elevation of the machine; Fig. 2 is a perspective view showing certain parts; Figs. 3 and 4 show a shoe before and after being subjected to the action of this machine. 60

The column 1 of the machine supports a head or frame 2 in which a cam shaft 4 has bearings and on which runs continuously a loose pulley 5 having in its right hand side a friction clutch face. A coöperating clutch member 6 is fast on the shaft as is also a cam hub 8. A spring 10 acts on a lever 12 to pull the loose member 5 toward the fast clutch member 6, said lever being guided by a slide 13 and having a steel block 14 by 65 which it is engaged by the left hand end of a swinging bar 15 that is carried on a lever 16 which has a roll in engagement with the cam hub 8. The latter acts through the lever 16 and arm 15 to swing the lever 12 70 toward the left for opening the clutch. For closing the clutch a latch 18 is connected to a tripping nozzle 20 so that upward displacement of the nozzle will pull down the bar 15, withdrawing it from the block 14, 75 after which the shaft makes one revolution during which the arm is withdrawn toward the right from under the block 14 and then lifted by its spring 19 and thrust toward the left against block 14 to reopen the clutch 80 and stop the machine. The shaft operates the tack pot and suitable tack feeding devices and also carries a driver lifting cam which raises the driver into position to be actuated by the spring operated arm 25 all 85 90 as usual in machines of this class.

From a treadle 30 extends a rod 32 to a lever 34 fulcrumed to the frame and connected at its rear end to the frame by a spring 35 which holds its front end down 95 as far as permitted by the engagement of the rear end of the rod 32 with the frame. The front end of the lever 34 is connected by a link 36 with a vertically sliding bar 38 having a thin forwardly lipped and 100 forked head 40 and guided in the frame. Above the head 40 is a coöperating clamping plate 42 formed with an eye and extending from a bar 44 guided in the frame and held normally depressed by a stiff 105 spring 45. The eye in the plate 42 is large

enough to receive the head of a shoe eyelet and is flared outwardly to present a lower edge adapted to engage the head of the eyelet close to the shoe upper to permit the shoe fly to be pulled or stretched with the aid of such engagement. Depression of the treadle 30 first raises the head 40, which is toothed on its upper face, to clamp a shoe fly which has been inserted under the plate 42 with an eyelet within the eye of said plate, the spring 35 yielding to permit the movement of head 40. A substantially greater force is required to move the plate 42 upward against the resistance of spring 45 and therefore opportunity exists for the workman to manipulate the shoe to stretch the upper while he holds the fly gripped by the treadle. This he does by rocking the shoe and its contained last, causing the last to fulcrum on the bar or work rest 38, or it may be, on fulcrum posts 46 which are suitably supported for this purpose on either side of the gripper 40, 42. Having turned and fulcrumed the shoe as observation shows to be required to pull the upper and it may be to stretch it for removing any fullness that may exist in the region of the waist of the shoe, the operator further depresses the treadle to overcome spring 45 and carry the fulcrum bar 38, the gripper and the shoe upwardly and engage the tripping nozzle and cause a tack to be inserted through the eye in the plate 42 and through the eyelet in the fly and into the last to maintain the upper taut until the last is withdrawn during which time it "sets" or acquires permanently the shape given to it on the last.

The invention is shown in Figs. 3 and 4 as employed in the manufacture of stitch-down shoes of which the uppers are molded at the toe and heel and are stitched to the innersole before the last is inserted. The insertion of the last and the subsequent shaping of the upper to the last constitutes the lasting of these shoes and the operation of this machine is particularly effective in shaping or lasting the waist portion of these shoes which frequently require care to get the upper free from fullness and to stand up to the shape of the last from the shank and forward portion of the heel seat upward to the shoe fly. By pulling the stock upward the middle portion of the innersole, as well as the upper is drawn snugly to the last where it is fastened by the tack driven through the eyelet, or it might be through a buttonhole or through any portion of the fly including the ankle strap of so-called ankle ties and other low shoes or slippers, and held while the shoe sets or acquires permanently the shape of the last and the stock dries more or less in that shape.

One advantage of this machine, as shown,

is that the operator works with the portion of the stock being manipulated plainly within sight and he can turn or vary the line or lines of strain to suit the existing conditions in each particular shoe and pull or draft the upper into desired shapeliness.

It is to be understood that this invention is not limited to use upon stitchdown shoes but may be used with good results upon other kinds of shoes.

It will be noted that this invention provides, for the first time as I am advised, means whereby a shoe upper may be pulled in the direction away from the shoe bottom and securing the pulled upper.

Having explained the nature of this invention and described a preferred construction embodying the same, I claim as new and desire to secure by Letters Patent of the United States all of the protection to which this invention is entitled and the following claiming clauses are to be construed to give effect to this purpose.

I claim—

1. A waist lasting machine, having, in combination, a gripper adapted to engage the fly of a shoe and hold it during relative movement of the gripper and the last to pull the fly in a direction away from the shoe bottom, and a fastening inserting mechanism located directly above said gripper and arranged to secure the fly to the last, after the fly has been pulled.

2. A waist lasting machine, having, in combination, means adapted to engage the fly of a shoe, last engaging means between which and the fly engaging means the shoe can be manipulated to effect a pulling of the fly in a direction away from the shoe bottom, and means arranged with relation to said other two means for securing the fly under tension.

3. A waist lasting machine, having, in combination, a gripper adapted to seize the fly of a shoe, means upon which the shoe can be fulcrumed while the fly is held by the gripper to effect a pulling of the upper in the direction of the extent of the fly, and fastening inserting means arranged with relation to said gripper and said fulcrum for securing the fly under tension.

4. A machine of the class described having, in combination, a tacker, gripper jaws constructed and arranged to occupy a position directly beneath the tacker with their gripping faces in planes at right angles to the direction of the tack inserting action of the tacker, and operating means to close the jaws and then move them toward the tacker.

5. A waist lasting machine having, in combination, a shoe fly seizing means comprising an outer member having a passage for the driver and a thin inner member adapted to extend between the fly and the last and having a passage for the tack, and

a power driven fastening inserting mechanism arranged in coöperative relation to said members.

6. A waist lasting machine having, in combination, a member shaped to fit and effect engagement with an eyelet in a shoe fly and between which and the last relative movement can be effected for tensioning the side of the upper from the shoe bottom toward the fly, and means to fasten the fly with the upper while it is held under tension.

7. A waist lasting machine having, in combination, a member adapted to encircle the top of an eyelet in a shoe fly and through which the upper may be pulled, and a tacker arranged relatively to said member to insert a tack through the eyelet.

8. A waist lasting machine having, in combination, a member recessed to engage the outer side of the top of an eyelet set in the fly of a shoe and between which and the last relative movement can be effected to tension the side of the upper upwardly toward the fly, and means for securing the fly through the eyelet with the upper held under tension.

9. A waist lasting machine having, in combination, means to engage the fly on one side of a shoe, means arranged at one lateral side of the engaging means in position to permit fulcruming of the opposite lateral side of the shoe thereon for pulling upwardly the side of the upper engaged at the fly, and means for securing the pulled side of the upper while the shoe is in such relation to said other two means as to maintain the pull on the upper.

10. A waist lasting machine having, in combination, means to engage the fly on one side of a shoe, means arranged to permit the fulcruming of the opposite lateral side of the shoe thereon for pulling upwardly the side of the upper engaged at the fly, and a tacker to which the engaging means is movable to carry the shoe into relation to the tacker for the tacker to insert a tack in position to secure the upper under tension at the waist of the shoe.

11. A waist lasting machine having, in combination, jaws recessed on their stock engaging faces to clamp the shoe upper around the upper and lower ends of an eyelet set in the fly on one side of a shoe, and means arranged to permit the fulcruming of the opposite side of the shoe thereon, the shoe and the last mentioned means being relatively movable to effect upward pulling of one side of the upper toward the fly.

12. A waist lasting machine having, in combination, means to engage the fly on one side of a shoe, a fulcrum arranged for engagement with the opposite side of the shoe, the fulcrum and said means being arranged to facilitate movement of the shoe relatively

thereto for effecting upward pulling of one side of the upper toward the fly, and means arranged to fasten the pulled side of the upper under tension at the waist of the shoe while it is held under tension between said fulcrum and engaging means.

13. A waist lasting machine having, in combination, jaws between which a shoe fly may be seized, operating means to close the jaws, means through which relative movement of the jaws and the shoe can be effected to tension the upper from the bottom of the shoe toward the fly, and means to fasten the upper, said operating means being constructed and arranged to effect movement of the shoe and jaws together to present the work to the fastening means after the upper has been tensioned.

14. A waist lasting machine having, in combination, an upper jaw, a lower jaw, an operating means arranged to raise the lower jaw to grip the stock against the upper jaw and hold it during relative movement of the jaws and last to pull the stock, and means to hold the upper jaw from rising while the stock is being gripped and pulled, and a fastening mechanism located directly above said jaws, said operating means being arranged to overcome the means which holds the upper jaw down and to raise both jaws and the work into operative relation to the fastening mechanism.

15. A waist lasting machine, having, in combination, a gripper adapted to seize the upper of a shoe, a fastening inserting mechanism located directly above said gripper and constructed and arranged to be rendered operative upon presentation of the work thereto, and operating means to cause said gripper to seize the upper and then to move said gripper and the shoe into position to cause the operation of said fastening inserting mechanism.

16. A waist lasting machine having, in combination, an upper jaw adapted to engage a shoe fly, a lower jaw adapted to enter between the last and the fly and having a downward extension rigidly connected thereto and adapted to serve as a fulcrum about which the last may be turned to pull the upper from the bottom of the shoe upwardly toward the fly, and means for actuating the jaws to seize the shoe fly.

17. A waist lasting machine having, in combination, a tacker, fly seizing jaws constructed and arranged to occupy a position directly beneath the tacker and movable upwardly toward and downwardly away from the tacker, and a shoe fulcrum located laterally adjacent to the jaws for engagement by the side of the forepart of the shoe and upon which the shoe may be fulcrumed to pull the upper in a direction away from the shoe bottom and hold it under tension for the action of the tacker.

18. A waist lasting machine having, in combination, a tacker, fly seizing jaws arranged below the tacker, and shoe fulcra located on either lateral side of the jaws to be engaged alternatively by the foreparts of right and left shoes and permit fulcruming of the shoes thereon to pull the upper toward the fly and hold it for the action of the tacker.
19. A machine of the class described, having, in combination, a frame, a tacker therein having a vertically arranged driver, gripper jaws located below the driver and in substantially the same relation to the plane of the front of the frame as is the driver, said jaws being adapted to engage the fly of a shoe, and a fulcrum located in a vertical plane between the driver and the frame of the machine in position to be engaged by the cone of the last, said parts being arranged and organized for use in pulling a shoe upper from the sole toward the fly and fastening the fly to the last.
20. A lasting machine, having, in combination, a fastening inserting mechanism constructed and arranged to be rendered operative by engagement of the work therewith,

a gripper adapted to seize the upper of a shoe, and treadle operated means to cause said gripper to seize the upper and hold it 30 during manipulation of the shoe to tension the upper and then to move the shoe into position to effect an operation of said fastening inserting mechanism.

21. A lasting machine, having, in combination, a fastening inserting mechanism constructed and arranged to be rendered operative by engagement of the work therewith, a gripper adapted to seize the upper of a shoe, a work rest upon which the last can be 40 fulcrumed to pull the upper relatively to the last, and treadle operated means by which the work rest and the gripper can be moved together with the upper under tension into position to cause the fastening inserting 45 mechanism to secure the tensioned upper.

In testimony whereof I have signed my name to this specification in the presence of two subscribing witnesses.

MATTHIAS BROCK.
